SUSPENDERS

Herbert P. Garren, Graysville, Tenn., and Bynum
J. Stepp, Hendersonville, N. C.

Application March 22, 1948, Serial No. 16,366

4 Claims.

(Cl. 2—340)

1 The present invention relates to new and useful improvements in suspenders and more particularly to interchangeable fastening means for attaching the suspenders to various types of fastening devices carried at the waist-band of a pair of trousers whereby the suspenders may be attached to buttons, snap fasteners or other types of fasteners carried by the trousers, as well as to provide means for attaching the suspenders to the trousers wherein the waist-band is not equipped with any type of suspender fastener.

An important object of the invention is to provide an interchangeable fastening attachment for the ends of suspenders and embodying means for easily and quickly attaching the fastener thereto.

A still further object is to provide an interchangeable fastening attachment for suspenders of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a view in elevation of a pair of suspenders equipped with round leather straps for fastening to the suspender buttons of a pair of trousers;

Figure 2 is an enlarged fragmentary vertical sectional view taken substantially on a line 2—2 of Figure 1;

Figure 3 is an enlarged perspective view of a modified suspender fastener;

Figure 4 is an enlarged perspective view of one of the attaching loops at the end of the suspenders for interchangeably attaching the fasteners thereto;

Figure 5 is a perspective view of a metal clasp provided with suspender attaching means and forming a further modified suspender fastener, and

Figure 6 is a vertical sectional view taken substantially on a line 6—6 of Figure 5.

Referring now to the drawing in detail, the numeral 5 designates generally a pair of suspenders which includes a single back strap 6 and a pair of front straps 7. Each strap 6 and 7 is provided at its lower end with a metal loop 8 from which a non-metallic loop of leather, cloth or other suitable material is suspended. Upper

and lower buttons 10 and 11 are suitably secured to one side of the non-metallic loops 9.

In Figures 1 and 2 of the drawings, the suspenders are shown provided with round leather fasteners 12 having heads 13 at their ends provided with button-holes 14 for engaging the buttons at the waist-band of a pair of trousers (not shown). The leather strap 12 is engaged in the rolled edge or eye 15 at the lower end of a rigid plate 16 constructed of suitable metal, plastic or other material, the plate having upper and lower key-hole slots 17 and 18 therein for respectively receiving the upper and lower buttons 10 and 11 of the loop 9 carried by the suspenders.

In Figure 3 I have illustrated a modified suspender fastener including the rigid plate 19 having the upper and lower key-hole slots 20 and 21 therein for engaging the buttons of the suspender loops 9 and flat leather straps 22 are secured in the eyes 23 at the lower end of the plate 19 by metal loops 24. The lower ends of the straps 22 are formed with the button-holes 25 for engaging the buttons of the trousers.

In Figures 5 and 6 of the drawings, the suspender fastener comprises a metal clasp 26 preferably constructed of strap metal bent upon itself to provide a pair of jaws 27 and 28. The end portion 28—A of the jaw 28 is offset and terminates in a substantially U-shaped gripping portion or loop 28—B that is yieldingly urged toward the end portion 27—A of the jaw 27 due to the resilient characteristics of the clamp 26 so that the waist band 29 of a pair of trousers will be gripped between the portions 27—A and 28—B. The jaw 27 is provided with a pair of forwardly projecting tongues 30 at its side edges having openings 31 therein and in which extensions 32 at the end of a locking cam 33 are rotatably positioned.

The cam 33 is integrally formed with and projects laterally from the lower end of a lever 34. The lever is provided with key-hole slots 35 for receiving the buttons 36 of the suspenders, the cam projecting inwardly for bearing against the jaw 28 to force the same into its closed position as the upper end 26—A of the clasp 26 is pivoted toward the lever 34.

The several types of fasteners shown in Figures 2, 3 and 5 may be interchangeably attached to the buttons 10 and 11 of the suspenders for use in accordance with the particular type of fastener carried by the trousers.

Having described the invention what is claimed as new is:

1. A garment suspender fastener comprising a

fastener element carried by the suspender, and a garment attaching member detachably secured to said fastener element, said garment attaching member including a plate attached to said fastener element, and a clasp pivotally carried thereby.

2. A garment suspender fastener comprising a fastener element carried by the suspender, and a garment attaching member, said garment attaching member including a clasp having a pair of complementary jaws, a lever rotatably carried by said clasp and detachably secured to said fastener element, and means carried by said lever for urging said jaws into clamping engagement.

3. The combination of claim 2 wherein said last mentioned means includes a cam at one end of said lever and bearing against one of said jaws when in clamping position.

4. A garment suspender fastener comprising a fastener element carried by the suspender and 20 having an outwardly projecting button, and a

garment attaching member, said member including a clasp having first and second complementary jaws, a pair of tongues carried by the first jaw, said tongues provided with an opening, a lever having a key slot receiving said button, a cam at one end of said lever bearing against said second jaw, and extensions on said cam pivotally mounted through the openings in said tongues of the first jaw.
